LOOPER MECHANISM FOR SEWING MACHINES

Andrew B. Clayton, Union, N. J., assignor to The Singer Manufacturing Company, Elizabeth, N. J., a corporation of New Jersey

Application November 30, 1931
Serial No. 577,919

17 Claims. (Cl. 112—200)

This invention relates to sewing machines of the chain-stitch type in which a reciprocating needle cooperates with an endwise reciprocating looper-blade.

5 An object of the invention is to provide a simplified and improved wide-gauge multiple-looper mechanism which is adapted for practical high-speed operation.

Another object of the invention is to provide a 10 novel looper throw-out mechanism which is adapted particularly for use with a looper-actuating mechanism, of the type disclosed in the patents to DeVoe, No. 1,100,124, of June 16, 1914, and to Clayton, No. 1,569,912, of January 19, 1926, 15 for shifting the looper from working position to a readily accessible position.

A further object of the invention is to provide 20 means facilitating the correct setting of the loopers relative to their respective needles.

With the above and other objects in view, as 25 will hereinafter appear, the invention comprises the devices, combinations and arrangements of parts hereinafter set forth and illustrated in the accompanying drawings of a preferred embodiment of the invention from which the several features of the invention and the advantages attained thereby will be readily understood by those skilled in the art.

Fig. 1 is a front elevation of the looper mechanism of a sewing machine embodying the invention. Fig. 2 is a top plan view of the looper mechanism. Fig. 3 is a rear elevation of the looper mechanism. Fig. 4 is a section on the line 4—4, Fig. 1, with the main-shaft turned 90° from the 30 position shown in Fig. 1 and the loopers in normal working position below the sewing machine throat-plate. Fig. 5 is a similar view with the loopers shifted to accessible position. Fig. 6 is a section on the line 6—6, Fig. 4. Fig. 7 is a section on the line 7—7, Fig. 6. Fig. 8 is a plan view of the upwardly spring-pressed plate shown in Figs. 6 and 7. Fig. 9 is a perspective view of a section of the main looper-driving shaft. Fig. 10 is a perspective view of the shiftable bearing 35 block for the looper-supporting spindles. Fig. 11 is a perspective view of one of the end-guiding brackets for the shiftable bearing block. Fig. 12 is a perspective view of a right angle guide-pin element of the looper-mechanism. Fig. 13 is a perspective view of the coupled looper-carriers. Fig. 14 is a diagrammatic view of the looper-driving elements, and Fig. 15 is a sectional view 40 through the guide-pin.

The sewing machine is constructed with the 45 usual bed 1, cloth-plate 2, throat-plate 3, feed-

dog 4, reciprocating needle-bar 5 and main drive-shaft 6. The needle-bar 5 is shown as carrying two widely spaced needles 7, 7 as is customary in wide-gauge machines.

Cooperating with each needle 7 is a thread-carrying looper 8 the blade of which is disposed transversely of the line of feed and has its loop-seizing and loop-shedding movements across the line of feed and its side-throw or avoiding movements in the line of feed. 60

The loopers 8 have their cylindrical shanks 8a mounted in clamps 9 at the upper ends of the twin looper-carrier levers 10 having bearing spindles 11 which are journaled in spaced parallel relation in the horizontal apertures 12 in the 65 detachable bearing-block 13; the axis of each spindle 11 being directly below or in intersecting relation with its respective needle 7. The looper-levers 10 are pivotally connected together at their lower ends by the yoke 14 having a central bearing aperture for the pin 15 the head 16 of which is split and is clamped to the depending sleeve-element 17 of the guide-pin 18 which is received in the central guide-aperture 19 in the bearing-block 13. The guide-pin 18 and its 70 sleeve-element 17 are normal to each other and are preferably made in one piece.

The main drive-shaft 6 is formed with the usual inclined crank 19 which is embraced by the long sleeve-head 20 of the vibratory drive-pin 85 21 which is normal to the axis of the sleeve-head 20 and works in the sleeve-element 17 and imparts rocking movements to the looper-carrier levers 10.

The axis a—a of the drive-pin 21 intersects 90 the axis b—b of the inclined crank 19 at a point 22 which is spaced from the intersection point 23 of the axis b—b of the inclined crank 19 and the axis c—c of the main-shaft 6. This spacing imparts a certain side-throw to the pin 21 and 95 causes the yoke 14 and looper-carrier levers 10 to slide with their spindles 11, endwise of the latter, to impart the desired side throw components of motion to the loopers; causing them to move, as usual, in elongated elliptical paths. 100

The function of the guide-pin 18 is to maintain the sleeve-head 20 of the drive-pin 21 in proper working position lengthwise of the inclined crank 19 which has no collars or other confining means thereon for holding the sleeve-head 20 against endwise movement. 105

It will be observed in Figs. 1 and 2, which show the loopers 8 at the ends of their respective retracting strokes and the inclined crank 19 in a vertical plane, that the cylindrical shanks or 110

pins 8' of the loopers 8 together with the sockets of the clamps 9 in which the pins 8' are fitted, are horizontally disposed and are parallel to the main-shaft 6. This provision permits the loopers 5 to be bodily shifted in the clamps 9 to set their points at the correct distance from their respective needles without raising or lowering such points. Also the loopers may be rocked on their pins 8' to adjust the lateral positions of the 10 loopers relative to their respective needles.

The detachable bearing-block 13 is mounted for up-and-down movement between the supporting guide-brackets 24 detachably secured by screws 25 to the bed 1. The inner faces of the 15 guide-brackets 24 are formed with grooves 26 which are curved concentrically with the axis of the main-shaft 6. These grooves 26 slidably receive the similarly curved ribs 27 on the end faces of the bearing-block 13. The bearing-block 20 13 has journaled therein a rock-shaft 28 bearing at one end a thumb-nut 29 and at its other end carrying a cam-shaped arm or strut 30, the end 31 of which, Fig. 6, bears upon the upwardly 25 spring-pressed plate 32 and supports and latches the bearing-block 13 in its upper horizontal working position in engagement with the overhanging lips 24' of the guide-brackets 24. The plate 32 is hinged at 33 to the pin 34 which is secured by the screw 35 in a socket in the bed 1. The 30 upward spring-pressure is applied to the plate 32 by springs 36, as shown in Figs. 7 and 8.

When it is desired to shift the loopers 8 to accessible positions, the thumb-nut 29 is turned to unlatch the bearing-block 13 and permit the 35 latter to drop from the position shown in Fig. 7 to that shown in Fig. 5, thereby turning the block 13 and the entire looper mechanism about the main-shaft axis as a center and carrying the loopers 8 forwardly of the throat-plate 3, 40 where they may be easily threaded. A turn of the knob 29 in a reverse direction elevates the block 13 and latches it in elevated position with the loopers returned to normal cooperative relation with the needles. Before throwing out the 45 loopers, however, the main-shaft should be turned to a point where the looper-blades are not behind the needles. Preferably, the needles should be raised above the throat-plate or the 50 loopers should be on their retracting stroke and hence in front of the needles, as shown in Figs. 4 and 5.

By providing a bearing element or block 13 for the guide-pin 18 and looper-spindles 11, which bearing element is movable laterally of said guide-pin and detachable from the sewing machine frame 1, the assembly and disassembly of the 55 looper-mechanism is facilitated, as it is not necessary to remove or disturb the main-shaft 6. The guide-pin 18 and its sleeve-head 17 may, 60 moreover, be made in one piece and may be installed or removed while the main-shaft 6 remains undisturbed in working position; a result which cannot be accomplished with the mechanism of the DeVoe Patent No. 1,100,124, and can 65 only be accomplished in the mechanism of my prior Patent No. 1,569,912, by making the horizontal guide-pin detachable as illustrated in such patent.

The present looper-mechanism is preferably 70 lubricated as follows: The bearing-block 13 is provided with a felt-packed cavity 37 which receives oil from a suitable source of supply and distributes it through ducts 38, Figs. 2 and 5, to the bearings for the spindles 11 and guide-pin 18. 75 The spindles 11 are hollow and take oil from

their bearings and carry it to and through the ducts 39, Fig. 4, in the looper-carrier levers 10 to the pivot-pins at the opposite ends of the yoke 14. The hollow guide-pin 18 conducts oil to its open inner end 40 from which the oil runs down the groove 41 and through the ducts 42 and 43 to the hollow pin 15 from which the bearing between the pin 15 and yoke 14 is lubricated. Oil from the groove 41 also lubricates the bearing between the sleeve-head 17 and the actuating pin 21.

Having thus set forth the nature of the invention, what I claim herein is:—

1. In looper mechanism for sewing machines, a main drive shaft having an inclined crank, a plurality of loopers, a plurality of looper-carrier-levers fulcrumed on axes which are parallel to one another and normal to the main shaft, a yoke pivotally connecting said looper-carrier-levers together, and an operative connection between said inclined crank and said yoke. 90

2. Multiple looper mechanism for sewing machines having, a plurality of looper-carrier-levers having spaced parallel spindles, bearings in which said spindles are journaled for rocking and sliding movements, a yoke connecting said looper-carrier-levers below their spindles, and means for imparting endwise and lateral movements to said yoke. 100

3. In looper mechanism for sewing machines, a main drive shaft having an inclined crank, a plurality of loopers, a plurality of looper-carrier-levers fulcrumed on axes which are parallel to one another and normal to the main shaft, a yoke pivotally connecting said looper-carrier-levers together, an operative connection between said inclined crank and said yoke, said operative connection including a sleeve embracing said inclined crank, a pin rigid with and normal to said sleeve, a second sleeve embracing said pin, and a second pin rigid with and normal to said second sleeve and journaled in said yoke. 110

4. In looper mechanism for sewing machines, a main drive shaft having an inclined crank, a plurality of loopers, a plurality of looper-carrier-levers fulcrumed to rock on spaced parallel axes normal to the main drive shaft, a sleeve embracing said inclined crank, a pin normal to said sleeve, a second sleeve on said pin, a second pin carrying said second sleeve and journaled in parallelism with the axes of rocking motion of said looper-carrier-levers, a yoke pivotally connecting said looper-carrier-levers, and a pivotal driving connection between said second sleeve and said yoke. 125

5. A main-shaft having an inclined crank, a looper, a looper-carrier, a bearing in which said looper-carrier is journaled, an operative connection between said inclined crank and said looper-carrier, and means for shifting said bearing about the axis of said main-shaft as a center. 135

6. A main-shaft having an inclined crank, a looper, a looper-carrier, a bearing in which said looper-carrier is journaled, an operative connection between said inclined crank and said looper-carrier, said bearing being shiftable about the axis of said main-shaft as a center, and a manually releasable element for supporting said bearing in normal sewing position. 140

7. In a sewing machine, a throat-plate, a main drive shaft having an inclined crank, a looper mechanism actuated by said inclined crank and including a looper having a blade performing endwise loop-seizing and loop-shedding movements below said throat-plate in opposite direc- 145

- tions, and means for turning said looper mechanism as a whole around said main drive shaft to carry the looper to an accessible position. 50
8. In sewing machine looper mechanism, a main-shaft having an inclined crank, a sleeve embracing said crank, a pin normal to said sleeve, a bearing member movable in an arc concentric with said main-shaft, a looper journaled in said bearing member on an axis normal to said main-shaft, and an operative connection between said pin and looper. 80
9. In sewing machine looper mechanism, a main-shaft having an inclined crank, a sleeve embracing said crank, a pin normal to said sleeve, a bearing member movable in an arc concentric with said main-shaft, a looper journaled in said bearing member on an axis normal to said main-shaft, an operative connection between said pin and looper, and manually releasable means for holding said bearing member fixed in sewing position. 85
10. In sewing machine looper mechanism, a machine-frame, a main-shaft having an inclined crank, a sleeve embracing said crank, a pin normal to said sleeve, a bearing member movable in an arc concentric with said main-shaft, a looper journaled in said bearing member on an axis normal to said main-shaft, an operative connection between said pin and looper, manually releasable means for holding said bearing member fixed in sewing position, said means including a manually operable rock-shaft journaled in said bearing member, and a latch-arm carried by said rock-shaft for cooperation with the machine-frame. 90
11. In looper mechanism for sewing machines, a bed, a main-shaft having an inclined crank, a bearing-block mounted on and movable relative to said bed about the axis of the main-shaft as a center, a looper, a looper-lever having a spindle journaled in said bearing-block, a sleeve embracing said inclined crank, a pin normal to said sleeve, and an operative connection between said pin and looper-lever. 95
12. In a sewing machine, a bed, a main-shaft journaled in said bed and having an inclined crank, a sleeve embracing said crank, a pin normal to said sleeve, a second sleeve embracing said pin, a second pin normal to said second sleeve, and a bearing element for said second pin detachable from said bed and movable together with said pin in a direction transversely of said pin's axis. 100
- pin, a second pin normal to and in one piece with said second sleeve, a looper connected to be operated by said second sleeve, and a bearing element for said second pin mounted on said bed and shiftable relative to said bed laterally of the axis of said second pin. 105
13. The combination with a reciprocating needle, a main-shaft, a looper cooperating with said needle, a pivotally mounted oscillatory looper-carrier operatively connected with said main-shaft, and an adjustable connection between said looper and looper-carrier permitting a bodily shift of the looper on its carrier in a direction normal to the needle when the looper is at the end of its stroke ready to begin its advance to seize a needle-loop. 110
14. The combination with a reciprocating needle, a main-shaft, a looper cooperating with said needle, a pivotally mounted oscillatory looper-carrier operatively connected with said main-shaft, and a pin-and-socket adjustable connection between said looper and looper-carrier, the axis of said connection being normal to the needle when the looper is at the end of its stroke ready to begin its loop-seizing movement. 115
15. In a sewing machine, the combination with a reciprocating needle, of a looper, a movable looper-supporting bearing, and a manually releasable element supporting the weight of said bearing in sewing position. 120
16. In a sewing machine, the combination with a reciprocating needle, of a looper, a movable looper-supporting bearing, a manually releasable element supporting the weight of said bearing in sewing position, and a spring-pressed thrust-member engaged by said manually releasable element. 125
17. In a sewing machine, a bed, a main-shaft journaled in said bed and having an inclined crank, a sleeve embracing said crank, a pin normal to said sleeve, a second sleeve embracing said pin, a second pin normal to said second sleeve, and a bearing element for said second pin detachable from said bed and movable together with said pin in a direction transversely of said pin's axis. 130
